ELECTRICAL AMPLIFYING CIRCUIT

Harry Hertwig, Berlin-Hennigsdorf, and Helmut Hintze, Berlin-Wendenschloss, Germany, assignors to General Electric Company, a corporation of New York

Application December 6, 1932, Serial No. 646,016
In Germany December 21, 1931

3 Claims. (CL 250—41.5)

Our invention relates to electrical amplifying circuits and concerns particularly arrangements for causing the operation of electrical devices in response to impulses which are either too weak 5 or of too short duration to cause the operation of said electrical devices directly.

It is an object of our invention to provide a simple, reliable, and easily constructed device for amplifying or for counting relatively short or 10 weak electrical impulses. Other and further objects and advantages will become apparent as the description proceeds.

In accordance with our invention in its preferred form, we utilize an electrical valve, preferably a vapor-discharge tube having a control grid to control the flow of current in an electrical device in response to relatively short or weak impulses. The control grid is normally negatively biased and the apparatus is so arranged that the 15 potential of the control grid is caused to rise in response to an impulse, thereby initiating a discharge in the discharge tube. The discharge having been initiated then continues for a length of time sufficient to operate the electrical device even though it be relatively slow acting. The discharge is then automatically terminated, restoring the apparatus to a condition for the reception 20 of the next impulse.

The features of our invention which we believe 25 to be novel and patentable are pointed out in the claims appended hereto. A better understanding of our invention, however, may be obtained by referring to the following description taken in connection with the accompanying drawing in 30 which Fig. 1 represents schematically the electrical circuit of one embodiment of our invention, and Fig. 2 represents a modification thereof.

Referring now more in detail to the drawing in 35 which like reference characters refer to like parts throughout, we have illustrated the application of one embodiment of our invention to the operation of electrical counting devices, but it will be understood that this example is given merely by way of illustration and our invention is not limited 40 thereto.

A discharge tube 11 of the gas or vapor-filled 45 type having a control grid 12 and having an anode 13 and a cathode 14 connected respectively to the positive and the negative sides of a source 50 of current 15 controls the operation of counting device 16 having an actuating coil 17 connected in series with the current source 15 and the discharge tube 11. The discharge tube 11 is of the type well known in the art in which the discharge 55 initiated by raising the potential of the control

grid 12 to a sufficient value continues thereafter irrespective of the grid potential until the anode potential falls below a value dependent upon the characteristics of the tube and referred to herein as the de-ionization potential. Discharge tubes of this type are referred to hereinafter as vapor-discharge tubes, and it will be understood that we mean to include by this expression all discharge tubes of the type just described whether their action is due to the presence of inert gas, metallic 10 vapor, or other gases, vapors, or mixtures thereof.

A suitable device or element having the characteristic of changing materially in resistance without the absorption of appreciable energy and preferably responding with relatively great rapidity, such as a photo-electric tube 18, is connected in series with a resistor 19 and a source of electromotive force such as a battery 20 between the anode and the cathode 14 of discharge tube 11. The battery 20 has its positive terminal connected 20 to the cathode 14, and the relationship between the resistance of resistor 19 and the normal resistance of the device 18 is such that the control grid 12 is normally maintained at a negative potential with respect to cathode 14, and the discharge tube 11 is therefore normally non-conducting. In the form of apparatus illustrated, the photo-electric tube 18 is exposed to the radiation of a lamp 21, and responds to light impulses produced by momentary illumination of the lamp or 30 to current impulses in the lamp filament which cause it to become illuminated. It will be understood, however, that if some form of variable resistance device 18, other than a photo-electric cell is to be employed it will be suitably arranged 35 to respond to the desired impulses, the exact nature of which does not form a part of our invention.

In order that the discharge in tube 11 may be self-extinguishing after current has flowed 40 through winding 17 long enough to operate the device 16, there are provided elements which may take the form of a resistor 21 connected in the anode circuit of the discharge tube 11 and a condenser 22 connected between the anode 13 of the 45 discharge tube 11 and the negative terminal of the current source 15. The winding 17 of the device 16 is inherently inductive and we find that the most satisfactory results are obtained by keeping the resistance of the circuit formed by 50 the discharge tube 11, inductive winding 17, and condenser 22 at a value sufficiently low to make the circuit 11—17—22 oscillatory. This may necessitate using a relatively low resistance winding 17. However, an equivalent result may be 55

obtained, as shown in Fig. 2, by substituting an inductance 23 for the winding 17 and connecting the winding 17 of the device 16 in one of the leads of the source 15.

5 In the operation of our device, the occurrence of an impulse causes the resistance of the device 18 (in the arrangement shown, a photo-electric tube) to fall to such a value that the current begins to flow through device 18, resistor 19, and battery 20, from the connection to anode 13 to the connection to cathode 14. The relationship between the resistances of device 18 and resistor 19 is then such that the potential drop in resistor 19 raises the potential of the grid 12 to a value 10 at which the tube 11 becomes conducting. Current then begins to flow from current source 15 through discharge tube 11 and winding 17, the action being the same whether winding 17 is connected in the position shown in Fig. 1 or the 15 position shown in Fig. 2. Owing to the character of the discharge tube 11, current continues to flow in the winding 17 even though the impulse affecting device 18 may have ceased, and the potential of grid 12 may have fallen again to its 20 normal negative bias. The continuance of the current through winding 17 permits the operation of the device 16, which may be of the slow-acting type or of a type which would not respond to the shortness of the impulse affecting device 18. 25 The constants of the resistor 21 and condenser 22 are so chosen that when discharge tube 11 becomes conducting, condenser 22 becomes partially discharged and thereupon the potential drop in resistor 21 causes the anode potential of the tube 11 to fall below the de-ionization potential of the 30 tube, extinguishing the discharge after sufficient current has flowed to operate the device 16.

In accordance with the provisions of the patent statutes, we have described the principle of 40 operation of our invention, together with the apparatus which we now consider to represent the best embodiment thereof, but we desire to have it understood that the apparatus shown is only 45 illustrative and that the invention may be carried out by other means.

What we claim as new and desire to secure by Letters Patent of the United States is:

1. A device for counting impulses of short duration comprising a vapor-discharge tube having 45 an anode, a cathode, and a control grid, a source of direct current, a resistor connected between the positive terminal of said source and the anode of said discharge tube, a condenser connected between the anode of said discharge tube and the negative terminal of said source, an electrical counter having an actuating coil with inductive characteristics connected between the negative terminal of said source of current and the cathode 50 of said discharge tube, a photo-electric tube having a pair of terminals one of which is connected directly to the anode of said discharge tube, a source of electromotive force having a pair of terminals, the positive of which is connected to the cathode of said discharge tube, a resistor of relatively high resistance connected between the remaining terminal of said photo-electric tube and said source of electromotive force, the control grid of said discharge tube being connected directly to the common terminal of said photo-electric tube and said last mentioned resistor so as to be normally negatively biased, and means 55 for illuminating said photo-electric tube in response to said impulses, thereby causing said photo-electric tube to become conducting per-

mitting the potential of the control grid of said discharge tube to rise and to cause said discharge tube to become conducting, thereby causing a current to flow through the actuating coil of said electrical counter so as to cause a potential drop in said first-mentioned resistor, reducing the anode potential of said discharge tube below the de-ionization potential and terminating the discharge of said tube after an interval sufficient to operate said electrical counter. 10

2. A device for counting impulses of short duration comprising a vapor-discharge tube having an anode, a cathode, and a control grid, a source of direct current, a resistor connected between the positive terminal of said source and the anode of said discharge tube, a condenser connected between the anode of said discharge tube and the negative terminal of said source, an electrical counter having an actuating coil connected in series with said source of current and said discharge tube and an inductance connected between the negative terminal of said source and the cathode of said discharge tube, an impulse-responsive device of variable resistance having a pair of terminals, one of which is connected directly to the anode of said discharge tube, a source of electromotive force having its positive terminal connected to the cathode of said discharge tube, a resistor of relatively high resistance connected between the remaining terminal of said impulse-responsive device and said source of electromotive force, the control grid of said discharge tube being connected directly to the common terminal of said impulse-responsive device and said last-mentioned resistor so as to be normally negatively biased, said impulse-responsive device being arranged to fall in resistance in response to said impulses, thereby permitting the potential of the control grid of said discharge tube to rise and to cause said discharge tube to become conducting, allowing a current to flow through the actuating coil of said electrical counter so as to cause a potential drop in said first-mentioned resistor, reducing the anode potential of said discharge tube below the de-ionization potential and terminating the discharge of said tube after an interval sufficient to operate said electrical counter. 40

3. An electrical circuit responsive to impulses of short duration comprising a vapor-discharge tube having an anode, a cathode, and a control grid, a source of a direct current, a resistor connected between the positive terminal of said source and the anode of said discharge tube, a condenser connected between the anode of said discharge tube and the negative terminal of said source, an inductive device connected between the negative terminal of said source and the cathode of said discharge tube, the electrical dimensions of said discharge tube, condenser, and inductive device being such that the circuit formed thereby is oscillatory, a device which falls in resistance in response to impulses and having a pair of terminals, one of which is connected directly to the anode of said discharge tube, a source of electromotive force having a pair of terminals, the positive of which is connected to the cathode of said discharge tube, a resistor of relatively high resistance connected between the remaining terminal of said variable resistance device and said source of electromotive force, the control grid of said discharge tube being connected directly to the common terminal of the variable resistance device and said last-mentioned resistor 50

so as to be normally negatively biased, whereby the occurrence of an impulse causes said variable-resistance device to fall in resistance permitting the potential of the control grid of said discharge tube to rise permitting a current to flow in said discharge tube so as to cause a potential drop in said first-mentioned resistor, reducing the

anode potential of said discharge tube below the de-ionization potential and terminating the discharge of said tube after an interval sufficient to operate said inductive device.
